(57) **CLAIM**

I claim the ornamental design for a helmet shaped cap for containers, as shown and described.

DESCRIPTION

FIG. 1 is a top plan view of the helmet shaped cap for containers;

FIG. 2 is front elevation view of the helmet shaped cap for containers;

FIG. 3 is a right side elevation view of the helmet shaped cap for containers;

FIG. 4 is a rear elevation view of helmet shaped cap for containers;

FIG. 5 is a left side elevation view of the helmet shaped cap for containers;

FIG. 6 is a bottom plan view of the helmet shaped cap for containers; and,

FIG. 7 is a front perspective view of the helmet shaped cap for containers.

The broken lines depict portions of the helmet shaped cap for containers that form no part of the claim.

1 Claim, 7 Drawing Sheets
